UNITED STATES PATENT OFFICE

127,965

DESIGN FOR A GLIDER

Aaron S. Goldberg, Philadelphia, Pa., assignor to
Bunting Glider Company, Philadelphia, Pa., a
corporation of Pennsylvania

Application February 3, 1941, Serial No. 98,676

Term of patent 7 years

To all whom it may concern:

Be it known that I, Aaron S. Goldberg, a citizen of the United States and a resident of Philadelphia, county of Philadelphia, State of Pennsylvania, have invented a new, original, and ornamental Design for a Glider, of which the following is a specification, reference being had to the accompanying drawing, forming a part thereof, wherein:

Figure 1 is a perspective view of the glider, showing my design;

Figure 2 is a top plan view thereof; and

Figure 3 is an enlarged view showing the per-

forations which are included within the laterally spaced panel sections in the seat and back of the glider, these perforations being continued throughout all of the areas in which they are partially shown in Figures 1 and 2.

The characterizing features of the present design reside in the all-metal glider, the seat and back panels of which are decorated by means of perforations in the areas as shown.

I claim:

The ornamental design for a glider, as shown and described.

AARON S. GOLDBERG.
